STAPLING MACHINE

George C. Passek, Philadelphia, Pa., assignor to
Alfred J. Paynter, Philadelphia, Pa.

Application February 9, 1939, Serial No. 255,422

3 Claims. (Cl. 1—49)

This invention relates to improvements in stapling machines of the type which includes a guide for a row of staples, a staple passage for receiving staples successively from the guide, a driver for driving the staples through the passage and into the work to be stapled, a follower for feeding the staples along the guide and a spring actuated follower for urging the staples forwardly along the guide and feeding them into the staple passage.

The object of the invention is to improve the mechanism for actuating the follower, whereby a more uniform pressure of the follower against the staples being urged forwardly may be obtained throughout the length of the travel of the follower, whereby the life of the spring may be increased, and whereby the spring may be easily placed under tension manually for successive staple feeding operations.

The invention resides in the novel construction, combination and arrangement of the elements of the mechanism as will be hereinafter described and claimed.

In the accompanying drawing, illustrating the invention:

Figure 1 is a longitudinal, vertical section of my improved stapling machine.

Figure 2 is a transverse, vertical section through a part of the machine, on line 2—2 of Fig. 1, enlarged.

Figure 3 is a sectional detail, on line 3—3 of Fig. 2, showing a part of the staple feeding mechanism.

Figure 4 is a sectional view similar to Fig. 3, showing a modification of the staple feeding mechanism.

Referring to the drawing, 4 designates the machine frame having a horizontally-extending lower portion 5 and a vertically-extending forward portion 6 rising from the forward end of the lower portion.

The lower portion 5 of the frame is hollow and has a floor plate 7 secured thereto and provided with a hollow, longitudinally extending staple guide 8 for receiving and guiding a row of staples 9.

The row of staples 9 is fed forwardly by a follower 10 which embraces the staple guide 8 and is slidably thereon and is urged forwardly by means presently described. The forward pressure of the follower 10 presses the foremost staple 11 of the row of staples against a plate 12 which is secured to the forward portion of the machine frame and provides the front wall of the vertically extending staple passage 13 whose rear wall

is formed by the forward end of the staple guide 8. The parts forming the passage 13 are of usual construction.

Slidably fitted within the forward portion 6 of the frame 4, above and in alignment with the foremost staple 11, is a staple driving plate 14 constructed and arranged to be moved downwardly from its normally elevated position shown in Fig. 1 and through the staple passage 13 to drive the said foremost staple 11 downwardly through the passage 13 and into the work being stapled, and to thereby discharge the staple through the open lower end of the passage.

The staple driver 14 has a bracket 15 secured thereto and pivotally connected to the lower end of a link 16 whose upper end is pivoted on a pin 17 carried by a lever arm 18 which is fulcrumed on a pin 19 in the forward portion 6 of the machine frame. The link 16 and the fulcrumed end portion of the lever arm 18 are housed within the machine frame, and the free end portion of the lever arm extends out through a slot 20 in the frame and forms a handle 21 which may be lowered and raised to effect staple driving operations.

The staple driver 14 and its operating lever arm 18 are maintained normally elevated by a spring 22 which is coiled around the fulcrum pin 19 and has one end thereof engaged with the pivot pin 17 and the other end thereof engaged with a transverse pin 23 fixed in the machine frame. The lever arm 18 is moved against the action of the spring 22 when the arm 18 is lowered to effect a staple driving operation, and, thereafter, the spring acts to elevate the arm to its normal position.

The follower 10 is provided with a part 24 which extends upwardly therefrom and into a longitudinal slot 25 in the lower portion 5 of the machine frame, and which is secured to one end portion of a windable element 26 which may be a cord or cable of any suitable material and construction. The other end portion of the element 26 is secured to the central cylindrical portion 27 of a rotatable member 28. This member 28 comprises a shaft portion 29 having its ends rotatably mounted in the side walls of the machine frame, and the cylindrical portion 27 which may be secured upon the shaft portion 29 or formed integrally therewith.

The cylindrical portion 27 of the member 28 is provided with annular end flanges 30, 30 between which the cable or element 26 is arranged to be wound upon or unwound from the cylindrical portion of the member.

The cable or element 26 extends forwardly from the follower 10 to and around the forward portion of an idler pulley 31 and thence to the cylindrical portion 27 of the member 28 to be wound upon the said cylindrical portion to move the follower 10 forwardly, when the element 26 is wound upon the cylindrical portion, and to be unwound therefrom when the follower 10 is moved in the reverse direction or rearwardly.

10 The pulley 31 rotates freely on a shaft 36 which is mounted in the machine frame.

Arranged on the respective sides of the cylindrical portion 27 of the member 28 and surrounding the shaft portion 29 thereof between the side walls of the machine frame and the flanges 30, 30 are two windable spiral springs 32, 32 having the inner ends thereof secured to the shaft portion 29 and the outer ends thereof secured or attached to a transverse pin 33 fixed in the machine frame.

20 The springs 32, 32 and the element 26 are constructed and arranged to be wound upon and unwound from the shaft portion 29 and the cylindrical portion 27 of the rotatable member 28, respectively, in reverse directions, so that when 25 the follower 10 is manually moved rearwardly, the rotatable member 28 will be turned in the direction of the arrows 34 in Figs. 1 and 3, by the unwinding of the element 26 to wind the springs 32, 32 upon the shaft portion 29; and, thereafter, 30 when the follower 10 is released against the rearward end of a row of staples upon the staple guide 8, the springs 32, 32, in tending to resume their unwound condition, will turn the member 28 in the direction of the arrows 35 in Figs. 1 35 and 3, and wind the element 26 upon the member 28, and thereby urge the follower 10 and the row of staples 9 engaged thereby forwardly.

The cylindrical portion 27 of the rotatable member 28 is of larger diameter than the shaft portion 29 thereof to enlarge the extent of the forward movement of the follower 10 with relation to the unwinding action of the springs 32, 32 in feeding the staples forwardly, and to increase the power of the pull of the element 26, 45 when the follower 10 is manually moved rearwardly and the springs 32, 32 are thereby wound around the shaft portion 29 of the rotatable member 28.

I have discovered that the construction and arrangement of the several elements and parts thereof of the devices for urging the staples forwardly along the staple guide 8, provides a mechanism in which the staples are urged forwardly by a more uniform pressure throughout the 50 length of the travel of the follower, than has been heretofore employed, that the springs act with greater efficiency in performing their staple feeding function, and that the springs may be wound with less manual effort when the follower 10 is moved rearwardly to be re-engaged with a 55 row of staples, following successive staple feeding operations.

In the modification illustrated in Fig. 4, the springs 32' are wound around the rotatable member 29' reversely of the direction in which they are shown in Figs. 1 and 3, and the element 26' is wound around the member 29' reversely of the direction in which it is shown in Figs. 1 and 3. This arrangement of the parts permits the idler pulley 31 to be dispensed with, and permits the cable or element 26' to extend directly between the rotatable member 29' and the follower 10.

I claim:

75 1. In a stapling machine, the combination of

a frame having a guide for receiving and guiding a row of staples, said frame having staple directing parts providing a passage for receiving and directing staples from said guide, a staple driver operable to drive staples through said passage, a follower movable along said guide for advancing a row of staples thereon and positioning them successively in said passage, a member rotatably mounted in the frame and having a shaft portion and a cylindrical portion of different diameter than the shaft portion, a windable spring having one end attached to said shaft portion and its other end attached to said frame and constructed to be wound around said shaft portion when the member is turned in one direction and to turn said member in the reverse direction by the unwinding action of the spring, and a windable element having one end attached to said cylindrical portion and its other end attached to said follower and constructed to be wound around the cylindrical portion of said member and thereby move said follower forwardly toward said passage when the member is turned in said reverse direction and to turn said member in the first named direction by the unwinding of said element when the follower is moved rearwardly from said passage, said shaft portion being laterally adjacent to said cylindrical portion, and said spring and said element being windable around said shaft portion and said cylindrical portion, respectively, in side by side relationship.

2. In a stapling machine, the combination of a frame having a guide for receiving and guiding a row of staples, said frame having staple directing parts providing a passage for receiving and directing staples from said guide, a staple driver operable to drive staples through said passage, a follower movable along said guide for advancing a row of staples thereon and positioning them successively in said passage, a rotatable member having a shaft portion rotatably mounted in the frame and carrying a central cylindrical portion having annular flanges at the ends thereof, two windable springs located on the respective sides of said cylindrical portion, each of said springs having one end attached to the shaft portion of said member and its other end attached to said frame and constructed to be wound around the shaft portion when the member is turned in one direction and to turn the member in the reverse direction by the unwinding action of the spring, and a windable element having one end attached to the said cylindrical portion of said member and its other end attached to said follower and constructed to be wound around said cylindrical portion between the end flanges thereof and thereby move said follower forwardly toward said passage when the member is turned in said reverse direction and to turn said member in the first named direction by the unwinding of said element when the follower is moved rearwardly from said passage.

3. In a stapling machine, the combination of a frame having a guide for receiving and guiding a row of staples, said frame having staple directing parts providing a passage for receiving and directing staples from said guide, a staple driver operable to drive staples through said passage, a follower movable along said guide for advancing a row of staples thereon and positioning them successively in said passage, a rotatable member comprising a shaft portion rotatably mounted in the frame and carrying a central cylindrical portion of larger diameter than the shaft portion

and having annular flanges at the ends thereof, two windable springs located on the respective sides of said cylindrical portion, each of said springs having one end attached to the shaft portion of said member and its other end attached to said frame and constructed to be wound around the shaft portion when the member is turned in one direction and to turn the member in the reverse direction by the unwinding action of the spring, and a windable element having one end attached to the said cylindrical

portion of said member and its other end attached to said follower and constructed to be wound around said cylindrical portion between the end flanges thereof and thereby move said follower forwardly toward said passage when the member is turned in said reverse direction and to turn said member in the first named direction by the unwinding of said element when the follower is moved rearwardly from said passage.
